THREE-PLATE METHOD OF AND APPARATUS FOR PRODUCING MAPS.

Application filed May 4, 1925. Serial No. 27,713.

This invention relates to topography, and more especially to a method of, and apparatus for, producing maps from aerial photographs; being more specifically directed to means for more accurately determining and describing elevations and contour lines.

The objects of my invention can be best understood if I first very briefly review the practice of map making by aerial photography as heretofore developed. The practice of flying an aeroplane over territory to be mapped and taking photographs with suitable camera equipment of successive sections of territory covered, and the subsequent cutting and piecing together of the developed pictures for making mosaic maps is well understood and in common use. One of the accomplishments unattained until recently, and only partially perfected, is the determination of elevations and contour lines from aerial photographs.

As a primary development in the art of map making I disclosed and claimed in my application for United States Letters Patent filed July 12, 1923, Serial No. 651,069, a method of and apparatus for producing maps which contemplates the projection of successive pictures upon a plane surface, a superimposed effect being thereby obtained and contour lines being defined by the proper adjustment of the position of, and the focusing of, the pictures with reference to the position of the camera at the time of exposure. This invention referred to employs telaescopic means for determining and photographically recording the altitude and position from which each successive photograph was taken, from which data computation could be made for properly projecting the images obtained in a laboratory. The photographs used in this prior method were taken upon a single line of flight, each photograph, of course, having a common overlapping area with the photographs immediately preceding and immediately succeeding. The successive pictures were projected by a pair of projectors singly aligned to correspond to the direction of the line of flight. This method is satisfactory in all but one respect, and that relates to the possibility of distortion upon the photographic plate due to deviation of the plate from the horizontal at the time of exposure; that is to say, there was no provision made for determining the amount of

and correcting for tilt, except by making measurements on the ground covered by each picture and determining the tilt by graphical means or by elaborate computation from these measurements. Such determinations are often entirely impractical for the necessity of penetrating inaccessible country on foot and making these measurements on the ground nullifies the advantage of the aeroplane. While extreme precaution may be taken, such as using a gyroscopically mounted camera, the art of camera mounting has not developed to such a state that the camera is strictly unsusceptible to tilt, which may occur from any of several conditions such as the sudden lurching of the aeroplane or from centrifugal forces introduced by imperceptible turns of the aeroplane. Variation from the horizontal of less than one degree will result in a considerable error when the uncorrected picture is reproduced upon a plane surface.

Thus, while photographs taken on a single line of flight may have been exposed in an approximately horizontal position there has been heretofore no practical and accurate way to determine this slight tilt at the time of exposure. The amount of this tilt is determined and correction is made possible by the apparatus and method hereinafter described wherein a third plate or photograph taken from a line of flight approximately parallel to a line intersecting the position of exposure of the first two photographs, or at least having an overlapping area with one or both of them, is superimposed in projection upon the first two images reproduced and the three plates adjusted until the resulting image projected from the three plates correctly defines the image of the contour selected.

Therefore:

An object of the invention is to provide a method and apparatus by which an accurate map may be produced from aerial photographs.

A further object is to provide in a method and apparatus of the class described means for selectively determining elevations and contour lines.

Another object is to afford means in a method and apparatus of the class described for determining and compensating for tilt of a photographic plate at the time of exposure; and to correct to a scale in the

projection thereof for any distortion due to tilt.

A further object is to facilitate the accomplishing of accurate registry of several 5 projected images of photographs.

A further object is to provide means for adjusting two plates simultaneously about an axis of indeterminate rotation or common 10 axis between the optical centers of their projection lenses.

Other objects and advantages will be made manifest in the following specification of an embodiment of the invention illustrated in the accompanying drawings in which:

15 Fig. 1 is a diagrammatic representation of two lines of flight from which photographs are taken.

Fig. 2 is a perspective view of the apparatus employed in the laboratory in the projection of developed photographs.

20 Fig. 3 is a plan view of the apparatus employed.

Fig. 4 is a vertical section of one of the projectors employed, detailing the mounting 25 thereof and is taken on the line 4-4 of Fig. 3.

Fig. 5 is a plan view partly in section and partly in diagram of a flicker device.

30 Fig. 6 is a horizontal cross section of a projector showing the plate holder in plan, being taken on the line 6-6 of Fig. 4.

Fig. 7 is an enlarged fragmentary view of a plate holder retaining means taken on the line 7-7 of Fig. 6.

35 Fig. 8 is an enlarged fragmentary section of the plate holder adjusting means, being taken on the line 8-8 of Fig. 6.

Fig. 9 is a diagrammatic view illustrating the principles of projection involved in 40 the method herein disclosed.

Fig. 10 is a diagrammatic representation of an overlapping, or superimposed effect, of three plates employed.

The first step in the procedure involved is 45 the taking of photographs of the territory to be mapped.

It is necessary that the altitude and location of the plane at the time of exposure be known; also the distance of separation or 50 interval between successive exposures. This may be accomplished by means of telaeroscopic information, details of which were disclosed in my co-pending application above referred to. Briefly, the telaeroscope is an 55 instrument by which vertical and horizontal angles can be readily determined and photographically recorded; this being accomplished by telescopes which are turned to hold the aeroplane at the cross hairs thereof 60 so that the elevation and position of the aeroplane can be computed therefrom. Referring to Fig. 1 it will be evident that as a result of the photographic record produced by the telaeroscope recording camera, data 65 will be obtained which shows the vertical

angle of the aeroplane at each telaeroscope, one being position at A' and a second at B, with reference to the first line of flight F, A'B being a known base line. The telaeroscope at the same time indicates the horizontal angle of the aeroplane with relation 70 to the ground base line.

The ground base line A'B, which may or may not be horizontal, is of a known length. The angles C and D are determined by the 75 telaeroscopes, as are also the angles G and H. The difference in elevation of the telaeroscope stations A' and B being known, it is evident that the distance AB is also known and that the dimensions of triangle AEB can be readily calculated since the two acute angles are known from the telaeroscope observations, and one side is a known base line. Therefore, by means of telaeroscopic observation the position of the point E for any 80 exposure can be readily calculated; or, in other words, the proper position in the map for the vertical point of each of the photographs taken by the camera from the aeroplane can be accurately and readily determined.

It will be evident, therefore, in connection with each of the photographs taken by the camera in the aeroplane, that by a simple 95 series of calculations, a known height above the reference plane and the vertical point at each photograph in the reference plane can be determined.

In the three plate method it is necessary 100 that a photograph be taken on a line of flight F', which is preferably parallel to the line of flight F, but the photograph may be any one having a common overlapping area with one or both of the photographs taken on the line of flight F. It should, however, be 105 so disposed that a triangle with good intersections is formed by the three points of exposure.

A duplication of the telaeroscopic method of determining altitude and position may be 110 employed, although, of course, any other method giving the same information would be equally satisfactory.

Assume for future reference that photographic exposures have been made at points 115 P, Q and R which have a common overlapping area readily defined, as illustrated in Fig. 10.

Having any two successive plates and a 120 third plate properly disposed with an area common to one of the other two taken from known elevations and with the horizontal distances between the respective points of exposure, that is to say, the air base lines, known or readily calculated from the information provided by the telaeroscope or other means employed, it is possible to readily 125 plot upon a map under construction any desired contour line. This is accomplished by an instrument which I term a three plate au- 130

topographer. The assembled autophotographer includes three projecting machines for projecting the image of the plates upon a plane surface, orients the plates, determines the 5 angular position of the plate at exposure and corrects for any departure from verticality of the optical axis.

The apparatus herein illustrated is extremely simplified to avoid confusion in 10 closure of the method employed. However, the necessary functions and elements have been included so that the method may be adequately explained.

Two parallel tracks 10 and 11 are disposed 15 above, and longitudinally of, a rigid tertiary table 12. Both tracks may be of channelled cross section affording upper and lower bearing surfaces for the slides of the projectors hereinafter described. Corresponding 20 scales 13 and 14 are provided on the upper faces of the channelled tracks to afford measurement longitudinally of the tracks for the purpose of properly locating the projectors X, Y and Z. A portion of the underside of 25 the upper horizontal extension of the channel tracks is formed with gear teeth 15 providing gear racks longitudinally of the tracks. The track 10 is mounted rigidly upon standards 16 which are supported by 30 the table 12, and the track 11 is provided with trunnion ends 17 and 18 which are adapted to rotatably seat in bearings provided by collars 19 and 20 which are formed 35 in the upper ends of standards 21. A portion of the peripheral surface of the annular end 17 is formed with gear teeth which are adapted to be engaged by a small pinion 22 keyed to the end of a stem 23 which is adapted to extend through the end of a projection from the collar 19 and to be operated 40 by a thumb wheel 24. The purpose of this arrangement is to afford a means for rotating the projectors X and Y upon an axis hereinafter referred to as the axis of indeterminate rotation, which in this particular 45 case extends through the optical center of the projecting lenses of the projectors X and Y.

All of the projectors are identical, the 50 only difference being in the method of mounting them. Projectors X and Y are carried upon the track 11 and projector Z is carried upon a transverse mounting 25, which is provided on its upper face with a 55 scale 26 similar to the scales 13 and 14.

The details of each projector and the mounting may be understood by referring to Fig. 4. Each projector comprises a substantially square housing 30 having a lower 60 tapered portion 31 which corresponds to a bellows extension, below the tapered portion, the housing being formed as a hollow ball 32, which is adapted to be supported by, and revolve in, a semi-spherical housing 33. 65 Below the hollow ball 32 is a short cylindri-

cal extension 34 which is adapted to retain a flicker device 35.

A set screw 27 is threaded through the housing 33 and is adapted to bear upon the hollow ball 32 for the purpose of securing 70 the projector in a desired position.

In the upper end of the housing 30 is provided an electric light source 36 behind which is disposed a reflector 37 and forwardly of which is placed a ground glass 75 38 for the purpose of light diffusion.

Condenser lenses 39 are retained below the ground glass by a circular strap 40 provided with an annular flange 41 secured to the interior of the housing 30. 80

One side of the housing is formed with an opening 45, which affords access to the interior of the housing for the purpose of manipulating a plate holder 46, and the opening 45 may be closed when the projector is in use by a sliding door 47. At the lower end of the sliding door 47 is secured a curved clip member 48 (see Fig. 4) and also a pivoted spring 49 which has an upwardly extending finger 50 adapted to be engaged by the clip 48 to deter the spring 49 from dropping to a vertical position when the sliding door is raised. The spring 49 comprises a flat resilient leaf terminating in a series of corrugations, and is intended to aid 95 in retaining the plate holder 46 in precise position for projection of the plate image. 95

The plate holder consists of a rectangular frame 51 provided with lateral tongues 52 which are adapted to slide in recesses 53 formed horizontally in a plate holder support 54 secured within the housing 30 and resting upon an angular support 55. The plate holder support 54 presents perpendicular faces 56 and 57 which may be employed 100 as locators for the proper disposition of the plate holder, and when the plate holder is pushed into the plate holder support 54 a pair of leaf springs 58 secured in a recess 105 parallel to one of the recesses 53 resiliently urge the plate holder against the surface 56, and when the sliding door 47 is lowered the action of the springs 49 yieldably urges the plate holder against the surface 57. The 110 plate holder may thus be always retained in the correct position, and if the plate carried by the holder is centered in the holder a correct projection may be made. 115

The means for adjusting or centering the plate 60 consists of 4 set screws 61, 62, 63 and 64 disposed one on each side of the rectangular plate holder and threaded horizontally through the plate holder so that each screw may bear upon the edge of the plate 60. It will be noted that a section of the plate 120 holder 46 resembles an L, thus providing a resting surface 65 upon which the plate may be disposed and a vertical extension 66 through which the set screws may be threaded. 125

The frame defined by the inner faces 67 of the plate holder 46 is adapted to accurately register with an image frame on the plate 60. At the time of exposure the border 68 of the plate should be properly masked in the camera so that a transparent border frame will be produced, the diagonals of which would intersect at the geometric center of the image. As this border frame 10 is the exact size of the frame presented by the plate holder the plate may be properly centered in the plate holder by manipulating the set screws 61 to 64, inclusive, at the same time holding the plate and plate holder 15 before a source of light to determine whether any lines of light are permitted to pass between the frame of the plate holder and the image frame of the plate. When the plate is properly centered in the holder no light will 20 be visible through the margins of the plate.

A projecting lens 70 is properly mounted so that its optical center is concentric with the hollow ball 32.

The spherical member 33 extends horizontally from a sliding support 71 which is adapted to enclose the track 11, and to slide longitudinally thereon. This sliding support 71 may be actuated by hand, but for a fine adjustment a small pinion 72 mounted 30 upon the inner end of a shaft 73, which bears in an aperture formed in the sliding support 71 and is adapted to be turned by a thumb wheel 74, engages the teeth of the gear track 15.

Set screws 75 may be employed for securing the projectors at any given position longitudinally of the track 11. The sliding support extending from the ball and socket joint of the projector Z is adapted to be moved 40 longitudinally of the support or mounting 25, that is to say, laterally of the tracks 10 and 11, and may be finely adjusted by a pinion operated on a gear rack provided in the lower face of the support 25. The sliding support 76 adapted to longitudinal movement on the track 10 is identical with the sliding support 71 with the exception that in 45 place of a spherical support 33 extending from the support 71 the transverse track support 25 is carried by the sliding support 76.

The flicker device 35 carried on the lower end of the cylindrical extension 34 comprises a housing 80 having an opening 81 very slightly greater than the diameter of the extension 34. A shutter 82 adapted to completely cover the opening 81 when swung below said opening is supported by an arm 83, which is pivoted at 84 and is adapted to be actuated by a solenoid 85 whose core 86 engages the arm 83. The pivotal connection between the core and the arm is very close to the pivotal mounting 84 of the arm so that the pulling of the arm 83 is sufficient to 60 65 swing the shutter 82 from one side of the

housing to the other. A coil spring 87 secured at one end to the core of the solenoid and at the other end to the housing 80 is adapted to work in opposition to the action of the solenoid.

When using the flicker device it is desired that the three should be operated successively, that is to say, while the shutters will be normally retained open by the springs 87 it is desired that each shutter should be momentarily closed, one after the other, when in operation. For this purpose I have provided a commutator contact arrangement diagrammatically illustrated in Fig. 5. A shaft 90 of a motor 91 is adapted to rotate a commutator 92 having a contact point 93 upon its peripheral surface which is adapted to successively engage three contact members 94. Each one of the contact members 94 leads by a wire 95 to a solenoid 85 and a wire 96 leads from the opposite end of the solenoid to a suitable source of electric energy herein illustrated as a battery 97. The rotation of the commutator 92 will cause the contact portion 93 to successively engage the contact members 94, thus completing the circuit through the solenoids of successive flicker devices and accomplishing the flicker effect desired.

Upon the rigid tertiary table 12 is mounted a secondary table 100, which is carried upon transverse tracks 101 and is adapted to be moved longitudinally of the tracks and transversely of the table 12 by a conventional worm arrangement, the details of which are not herein shown, the movement being accomplished by rotation of the thumb wheel 102. The secondary table 100 is provided with longitudinally extending tracks 103 upon which a double primary table 104 is adapted to slide, being moved thereon by a conventional pinion arrangement, the details of which are not herein shown, and which may be operated by a thumb wheel 105. The primary table 104 is provided with cross lines 106 and 107, which may be used for orienting the pictures projected, and for following contour lines or locating points, if desired. The primary table 104 comprises two thicknesses, identical in outline, the upper thickness being pivoted at the underside to swing upon an axis perpendicular to the intersection of the cross lines 106 and 107. It is upon the upper thickness of this primary table 104 that the picture images are projected.

A plotting table 108 is extended from the tertiary table 12 and is provided with a pantograph 109 carrying a tracing instrument 110. An arm 111 extends from the pantograph proper and is secured to the primary table 104, the movement of which is adapted to actuate the pantograph for describing contour lines which appear in the projected images.

Referring to Figs. 9 and 10 I will now proceed to a description of the method employed in the use of the apparatus just described.

- 5 Three plates are used which I will designate as plates P', Q' and R'. Plates P' and Q' may be successive plates taken from the aeroplane at a distance appearing as PQ on the line of flight F, which will hereinafter 10 be referred to as the air base line, and plate R' is taken possibly from the next overlapping row so as to have an overlapping area common with plate P' or Q', or both. Any 15 two plates with a common overlapping area give all information necessary to map different common areas, with the exception of the angle of the plate at exposure. The third plate permits the determination of this angle.
- 20 Plates P' and Q' are first placed in projectors X and Y, in which the flicker devices 35 are caused to remain open for the purpose of making the necessary adjustments. The images will be at approximately 25 ly the same scale by virtue of the point of exposure having been at the same elevation.
- It is next necessary to provide for orientation of the two plates. The two plates are 30 adjusted so that the projection of their geometric centers falls on the longitudinal cross line 107 of the primary table 104. The two projectors X and Y are at this time preferably longitudinally separated so that the images do not overlap on the table 104.
- 35 The plates are then adjusted about the vertical axis by rotating the projectors in the ball and socket joints so that the projected images extend very nearly in the same direction.
- 40 A readily distinguished object is then picked out which appears in both plates, and the table 104 is moved until the selected object is projected from one plate on the line 107. The other plate is then turned by a 45 slight rotation of the projector on the vertical axis until the projection of this selected object from the other plate also strikes the longitudinal cross line 107. It is sometimes necessary to make several adjustments on 50 several different points of the plates before accurate orientation can be produced. In other words, the two images of each object when the plates are properly oriented and otherwise corrected as to altitude and angle 55 of exposure will always fall in a longitudinal line, that is, in a line parallel to the line connecting plate centers.

However, the orientation as described cannot be accurately accomplished until the 60 plates have been corrected for tilt, for, in fact, these two adjustments are interdependent and must be accomplished together.

An error in orientation may be discerned from an error in tilt, for if the error is in 65 orientation only a slight rotation of the

plates will cause the lines connecting the corresponding images of all common points to become parallel. If a tilt is present it will be at once apparent for it will be impossible to make these lines parallel by orientation. 70

After orienting as closely as possible, the plates P' and Q' are moved together to a plate base line distance computed to give any desired contour line. That this may be accomplished can be understood by reference to Fig. 9. At a given distance of separation of the plates P' and Q' an image projected through the lens L will intersect only upon a single horizontal plane. 75 That is to say, if the image I (being of a point taken on the horizontal plane AB) were projected from the plates P' and Q' simultaneously and the plates were disposed at the time of projection in the identical 80 position which they occupied at the time of exposure, the intersection of the lines of light 1 will occur only upon the plane AB. Furthermore, the lines of light to any object in a different contour plane such as 85 the planes CD and EF will not intersect at the plane AB, but will show double images out of registry, causing a blur, at this elevation. Now, the same principle applies 90 when the images are projected in miniature at the same proportion. Thus, if the plates P' and Q' are separated a distance to bring the images appearing on the contour plane AB into registry, objects appearing in any other elevation such as CD or EF will not 95 intersect and will appear as a blur. Now the points of various elevations may be brought into registry by either varying the elevation of the plane surface upon which the images are projected, such as lowering the 100 table to CD or EF, or by moving the plates P' and Q' closer together in order to obtain registry of the images of lower elevation. Thus, it will be seen that the contour points of any elevation may be brought into registered projection by adjusting the distance 105 of separation of the plates. 110

The flicker device is set in operation and the resulting image observed. It will be apparent that in the flicker effect obtained, 115 only the lines of a contour which intersect at the particular elevation for which the setting is made appear to be in focus, and consequently will not be disturbed by the alternate flicker of the two projectors X and Y, while all portions of the projecting images which do not register, that is, which are not on the contour chosen, will appear as a blur wherein no object will be discernible. 120

While the flicker devices 35 are extremely useful in the three plate method of this invention, they may also be used in a two plate method to produce an illusion in which contours become apparent in the overlap- 130

ping portions of the images of these photographs, as set forth in my application No. 651,069, filed July 12, 1923, on method of producing maps.

5 In producing contours by this method as described thus far, I have assumed that the plates were taken with the camera axis directly vertical. In practice this is seldom the case, and, consequently, it is necessary to 10 determine the amount, and direction of this error which I have called tilt, and to provide correction for it.

It is a well established fact that a photograph of a horizontal surface taken with a 15 tilt or inclined camera axis does not record the objects on this horizontal plane at a uniform scale. Tilt, by the laws of perspective introduces a variation in scale.

However, by placing the plate so exposed 20 in a projecting camera, the axis of which is in the same angular position as was the axis of the exposing camera with the lens of a suitable focal length to maintain the lines of light at the same angle as they were 25 at exposure, the projected image will strike a horizontal surface at a true and undistorted scale.

Upon the first trial, excepting in very rare 30 occasions, there will not be a clear cut line of no motion. This is because of a tilt in one or both plates. Instead of a line of no motion there will be an area of slight motion. The plates should again be rotated slightly 35 to make certain that the orientation is as close as possible. If this fails to produce a perfect line the tilt may be determined and corrected by trial and error in the following manner.

40 Swing the plates about the optical lens center, which may be readily done by virtue of the freedom permitted by the ball and socket mounting of the projectors, until the images appear to be more nearly merged while flickering. Next choose several points 45 from the area of least motion. It is preferable although not essential to choose four such points and they should be readily identifiable on each plate. If convenient two of the points should lie on opposite sides of 50 the plate center line from the other two.

If the relative error in tilt is large the operator will see at a glance the approximate situation which is causing the discrepancy, for the images from the two plates 55 will be out of register. One or both plates must be tilted to bring the images into approximate superimposition. Then if the left two points of one of the plates are much further apart than the corresponding two 60 points of the other plate, as observed under a slow flicker, and the right two points are much closer together, it is obvious at once that there is a tilt about the lateral axis in both plates. It is evident that one plate 65 alone could not be tilted to correct to satis-

faction, since such a tilt would again displace the whole image horizontally causing a large discrepancy between all points. Both plates must be tilted in the direction indicated by this observation until the left and right points in the two plates are both as close to superimposition as possible.

Then flicker rapidly. If there is still some motion apparent in what was formerly the area of least motion, rotate the plates slightly to check the orientation. If this fails to produce sharply defined lines there is still some tilt correction necessary. Observe the four points to ascertain if they are still in the area of least motion. If any or all of them are moving further while flickering than other points in the area of least motion, new points should be selected from this area. Flicker slowly. Perhaps now the further pair of points appear more widely separated in one plate than in the other, while the nearer pair appear close together. This indicates a relative tilt about the longitudinal axis and both plates must be tilted about this axis to a position where the area of least motion approaches closest to a line. Orientation is rechecked, a new set of points selected, if necessary, and the process continued until the area of least motion is reduced to a line.

95 The plates P' and Q' are now properly oriented and have no relative tilt. The only error which may still be present is one of equal angular displacement of the two plates about the base line axis. In other words, if instead of a horizontal table there were a vertical table the same distance from the plate base line, both projectors could be rotated on the track 11 through 90° and in the resulting image the same line of no motion 100 would be intact.

In fact, this same situation could be present in any plane tangent to the plate base line axis, which in this connection may appropriately be called the axis of indeterminate rotation.

110 Practically speaking, the axis of indeterminate rotation of the projectors herein employed passes through the projecting lenses 70, and the bearing provided by the collars 19 and 20 affords means of rotation about the axis of indeterminate rotation. A false registry may occur at the intersection of the primary table with some tangent plane perpendicular to the vertical axis of the two 115 plates if they lie incorrectly placed about this axis of indeterminate rotation. The operator seeing a registry from two plates, therefore, has no way by the use of two plates to know the proper disposition about 120 this axis.

125 It is to provide this correction that the third plate R' is used.

Plates P' and Q' are left in the position 130 where they produce a sharp line. No fur-

ther adjustment will be necessary on them, excepting a rotation about the axis of indeterminate rotation or plate base line axis, which may be accomplished with plates P' and Q' maintained as a unit on their track, rotation occurring by turning the thumb wheel 24, which, through the stem 23, operates the pinion 22 on the threaded portion of the collar 19.

10 Plate R', after having been placed in its proper position by reference to the data obtained from the telaoscopes, or other instruments, and reduced to the proper proportions on the scales of the track 10 and the 15 transverse support 25, is next approximately oriented with either plate P' or Q'. All adjustments will be more easily accomplished while using projector Z with either projectors X or Y, but not both. Orientation of the plate R' is accomplished with the longitudinal line 107 turned to intersect the image center of plate R' with either P' or Q'. In order to determine where this image center is, it will be necessary to provide on each 20 ball and socket a mark 88 on the ball, which will register with the opening at the upper end of the socket or semi-spherical support 33 when the lense axis is vertical. Then the center of the image will represent the point 25 vertically below the plate center for the purpose of orientation. After orienting proceed to eliminate the tilt between R' and P', or Q', precisely as described already, with the exception that plate P' or Q' is only to be tilted by rotation on the axis of indeterminate rotation, and, of course, will carry the other plate with it. This adjustment is more easily made ordinarily than the adjustment between plates P' and Q'. Since plate 30 P' or Q' can only move about the one axis, it is merely necessary to carry the rotation through the probable angle of error trying to make plate R' register as the rotation progresses. When an adjustment is accomplished to the point where a true line of no motion occurs the correct position has been obtained to compensate for all errors of tilt, and true contours and other information may be obtained from the three plates. If 35 plate P' were used with R' it is advisable, as a final check, to flicker Q' with R' and then all three together. If there is no motion it is proof that all corrections have been properly made. That is to say, the corrections 40 for orientation and tilt are accurate. If there is a discrepancy in this final line of no motion, or any other for that matter, a mistake has occurred some place in the system and it will be necessary to systematically 45 check back through to discover it.

A slight modification of this procedure is necessary in special cases, such as a uniformly sloping plane where contours would be straight and parallel. In this case two 50 points in one area of least motion for a high

contour would be used and two points from a lower area with the plate centers moved closer together for a lower contour.

On each adjustment the plate centers would have to be moved twice to bring the 55 respective sets of points into the area of least motion or contour line, as the case might be.

In precise work it may be preferable to replace the ball and socket by a gimbal mounting. With this arrangement it is also 60 possible to introduce an arc on each axis by means of which angles may be read so that one three-plate adjustment will suffice for all time, by making a permanent record of the angles. It may further prove desirable 65 to include slow motion screws of conventional design to facilitate the handling of the projectors for precise work.

The infallibility of the method described may be explained in this manner. Cameras 70 replaced into the positions of exposure at P' and Q' and used as projectors for the developed plates would cause the rays of light to fall back exactly on the source from which they came. Refer to Fig. 9. Imagine a huge level table of adjustable height, covering the entire area photographed. Sharp images would only register for those points with the two rays of light intersecting at the table. All other points higher or 75 lower would show double images, such as would occur between lines of light 1 passing through the plane, or table AB. Therefore, the rays of light from two overlapping pictures projected in miniature of the actual 80 conditions onto a horizontal table must intersect at the imaged object in miniature.

Only at the correct relative angle of the projectors could there be superimposition 85 on this horizontal table. Although a single 90 point, or series of points, from two plates might in unusual cases fall into registry; off this axis superimposition could not occur and falseness of the registry would at once be disclosed by the third plate, for if the 95 plate images upon which the distances from images to table, resulting from tilt, were too great they would enlarge too much, while if these distances were too short the enlargement would not be enough. That is to say, 100 this false registry might occur from the equal slight tilt of each projector about a lateral axis. Both images in effect would be moved closer together in case each projector were tilted toward the other through 105 an equal angle, and a false registry might occur on a series of points. But on account of the tilt the light from two points of the series will have to travel farther to the table, hence the images of the two points will appear at too large a scale. The third plate 110 image if in its correct position will not register because its projected image of the two points will be to true scale. If on the other hand the first two plates are tilted 115 120

125 130 135

about the axis of indeterminate rotation, then the projected image of the third plate will fail to register due to its distortion from the tilt necessary to bring the images to approximate registry. This condition will prevent registry since the distortion is relative to a perspective point displaced relative to the perspective points of the other plates.

In order to produce a contour line by the flicker process it is, therefore, essential that the projection from the two plates occur at the same scale, in the same plane. Since all photographs are exposed from the same elevation, or corrected to the scale of the same elevation, it is obvious that the points of the same scale and in the same plane must lie in a plane parallel to the plate base line axis. By taking the third plate on a plate base line axis making a large angle with the other axis there is only one situation where the three will simultaneously produce a line of no motion. This situation occurs with all projectors replaced into the angular position of exposure and projected onto a horizontal surface, or surface parallel to a plane passing through the center of the projecting lenses, which is a horizontal plane. This, of course, presumes that the three plates were exposed from the same altitude or corrected for this error.

When the projected images have been accurately defined upon the primary table 104 the operator may follow the contour lines with the intersection of the cross lines on the table 104 and the pantograph will reproduce a contour line such as 115 upon the plotting table 108. As before pointed out, any other contour lines such as 116 may be determined and plotted by properly adjusting the separation of the projectors, as hereinbefore outlined.

There may be occasions in very rare instances where the data obtained in the plates P' and Q' will be sufficient to correct for tilt. This may occur where photographs have been taken along the ocean shore, where it is obvious that a known contour line will appear, or in country replete with erosive formations wherein the strata are very regular and of known position. In these instances the correct tilt may be ascertained by adjusting the plates to register on the known contour. There is only one point at which the projected images of the known contour lines will perfectly register along their entire overlapping length. If the plates were in any but the position at which they were during exposure the projected image, by virtue of the diagonal disposition of light rays would cause the superimposed image to fail of registry at the extremities of the known contour.

I claim as my invention:

1. A step in the art of map making comprising: taking three photographs of terri-

tory to be mapped having a common overlapping area; determining the point of exposure of each photograph; projecting in miniature of the arrangement of exposure the photographic images upon a common field; and determining by observation and adjustment of the superimposed images the exact angular position of each negative at exposure.

2. A step in the art of map making comprising: taking photographs of territory to be mapped having a common overlapping area; projecting the images from the photographs upon a plane surface; causing the projected images to superimpose so that image objects occurring at a given elevation approximately register; and perfecting said registration by determining and correcting for equal angular displacement of two of the photographs about an axis of indeterminate rotation by the use of a third photograph.

3. A step in the art of map making comprising: taking photographs of territory to be mapped having a common overlapping area; rapidly and alternately projecting the photographic images upon a common field; and determining by observation and adjustment of the superimposed images the exact angular position of each negative at exposure.

4. A step in the art of map making comprising: taking photographs of territory to be mapped having a common overlapping area; rapidly and alternately projecting in miniature of the arrangement of exposure the photographic images upon a common field; and determining by observation and adjustment of the superimposed images the exact angular position of each negative at exposure.

5. A step in the art of map making comprising: taking photographs of territory to be mapped having a common overlapping area; determining the point of exposure of each photograph; rapidly and alternately projecting in miniature of the arrangement of exposure the photographic images upon a common field; and determining by observation and adjustment of the superimposed images the exact angular position of each negative at exposure.

6. A step in the art of map making comprising: taking photographs of territory to be mapped having a common overlapping area; rapidly and alternately projecting the images from the photographs upon a plane surface; causing the projected images to superimpose so that image objects occurring at a given elevation approximately register; and perfecting said registration by determining and correcting for equal angular displacement of two of the photographs about an axis of indeterminate rotation by the use of a third photograph.

7. An apparatus to be employed in map

- making comprising: a plane surface adapted to receive projected images; a plurality of projectors mounted to project images upon a common area of said plane surface; means 5 permitting individual rotation and adjustment of said projectors; and means independent of said last named means for simultaneously rotating a pair of said projectors on an axis parallel to and longitudinal 10 of the plane surface.
8. An apparatus to be employed in map making comprising: a plane surface adapted to receive projected images; a plurality of projectors mounted to project images upon 15 a common area of said plane surface; means permitting individual rotation of said projectors; means independent of said last named means for simultaneously rotating a pair of said projectors on an axis parallel 20 to and longitudinal of the plane surface; and flicker devices mounted on each projector and adapted to interrupt the issuance of projected light rays.
9. An apparatus to be employed in map 25 making comprising: a plane surface adapted to receive projected images; a plurality of projectors mounted to project images upon a common area of said plane surface; means permitting individual rotation of said projectors; means independent of said last 30 named means for simultaneously rotating a pair of said projectors on an axis parallel to and longitudinal of the plane surface; flicker devices mounted on each projector
- and adapted to interrupt the issuance of 35 projected light rays; a plate holder in each projector; and means for centering a plate in said holder.
10. In map making, the art which comprises: taking photographs of territory to 40 be mapped, said photographs having a common overlapping area; projecting the images of said photographs upon a common field; adjusting two of said images into an approximately true relation with each other; 45 and, while maintaining said relation between said two images, adjusting said two images and a third of said photographic images into an approximately true relation with each other and perfecting said relation by adjustment of the three images into perfect registry, the relation thus set up between said three images causing the photographs in the projectors to occupy the same relative angular positions as held by said photographs when taken, and constructing a map 50 from the resulting information.
11. A method of producing a contour map, consisting of projecting the images of overlapping photographs onto a surface and determining all objects in a given contour by rapidly and alternately projecting the images onto a common surface to determine the exact points of registry.
- In testimony whereof, I have hereunto set 65 my hand at Los Angeles, California, this 27th day of April, 1925.
